COMB MAKING DEVICE

Carl Teber, Berlin-Karishorst, Germany

Application March 8, 1932, Serial No. 597,521,
and in Germany September 9, 1931

25 Claims. (Cl. 144—26)

My invention refers broadly to the manufacture of combs, particularly from organic more or less resilient material, such as horn, hard rubber, vulcanit, artificial horn and the like and it is intended among other objects and advantages to devise means of facilitating and simplifying the course of manufacture, to increase the output of marketable articles and to generally improve the appearance and usefulness of the products. In view thereof it is one of the important objects of this invention to devise means of cutting the gaps of one or of a plurality of combs or of groups thereof simultaneously or in one operation and in connection therewith it is a further object of the invention to produce combs in which the teeth and the width of the gaps between them are very uniform, which heretofore has constituted a very difficult problem. These and other objects of the invention are accomplished by disposing the crude working blocks or plates from which the combs with their teeth are to be manufactured between substantially adapted to be moved relative to each other so as to retain the piece of work in position and grate-like guiding means between which the cutting blades or the like are guided during the cutting operation. The means employed for this purpose are preferably aggregate cutting devices which may for instance be constituted by a plurality of band-like or circular serrated cutting means or punching knives serially arranged side by side of each other. The kind of tools employed in the particular case is generally governed by the nature of the material to be operated upon and the shape of the blocks or pieces of work under treatment. In the case of material, such as hard rubber for instance, which offers a great resistance to the cutting means, it is preferable to employ band-like or circular blades, while the piece of work may, if desired, be provided with grooves or flutings to facilitate the operation, but it should be understood that the operation does not depend upon such preliminary treatment. Punching or stamping knives may be employed in the case of thin combs and of material that is easily cut as for instance various kinds of artificial raw material and also in case of such pieces of work with preliminarily impressed grooves or gaps in which it is only necessary to sever a relatively thin web which has remained between the teeth in the pressing operation. The cutting tools employed are adapted to produce straight as well as bevelled gaps. The band-like cutting blades and punching or stamping blades are preferably construct-

ed so as to finish the cutting operation by a single working stroke and they are preferably arranged somewhat in the manner of grooves-producing bars or needles or similar instrumentalities, and in a modification of the invention they may be so arranged and constructed as to be suitable for the manufacture of undulatory gaps and teeth. In a preferred embodiment of the invention lamellated guides may be employed for the cutting blades and these guides may also serve for the positioning and supporting and, whenever desired, for the depression of the working piece.

In further pursuance of this invention means are provided of operating on combs with preliminarily impressed teeth in which the knives are guided by the guiding means or the like in exact alinement with the previously produced grooves or depressions. This object is accomplished in accordance with the invention by the fact that the lamellated guides are arranged to be laterally movable or engageable with yielding elastic or resilient means, the said lamellated guides being preferably provided with indented portions for the previously impressed teeth at their side confronting the piece of work. By forcing these guides against the piece of work or by moving the latter with relation to the guides the said lamellar guides will be caused to partially grip or encompass the previously impressed teeth of the comb and will then yield and extend and will guide the cutting blades which are likewise laterally movable or yieldable, so as to occupy the exact positions of the previously impressed grooves of the comb.

The lamelle or leaves of the guiding means constitute a kind of grate which like the cutting blade guided thereby are disposed between adjustable stops by the displacement of which the spacing of the cutting blades or of the guides may be accurately adjusted from the first to the last gap.

While in this specification and in the appended claims for explanatory purposes the cutting means may be referred to as cutting knives or blades, it should be understood that such terms should be interpreted generically, so as to comprise the substantially band-shaped, circular or stampingly operating or punching, milling, sawing, or similarly acting tools already referred to. The invention will be more fully described by reference to several preferred kinds of embodiments shown in the accompanying drawings without however restricting the invention to these exemplifications.

In the drawings: Fig. 1 is an exemplification with parts in section of one embodiment used in connection with band-shaped cutting means. Fig. 2 is a section on the line T—U of Fig. 1.—Fig. 5 is a plan view of the lower frame for the laminated guides with the depressing means removed.—Fig. 4 is an enlarged section on the line V—W of Fig. 1.—Fig. 5 is the fastening frame for the lamellar guiding means on an enlarged scale, this figure also embodying several other exemplifications of parts of the invention. Fig. 5a is an elevation in part in accordance with the illustration of Fig. 5 showing a modification of the spacing means.—Fig. 6 is an elevation with parts in section of a modified construction of the invention.—Figs. 6a—6d are sections through a knife blade according to Fig. 6.—In Fig. 7 is shown an elevation of the machine in part section and supplementing the representation of Fig. 6.—Fig. 7a is a plan view of the upper knife holder.—Fig. 8 shows a comb manufactured according to this invention.—Fig. 9 is a plan view of a supporting grate with guiding lamellæ and knives, the latter being shown in section.—Figs. 10 and 11 illustrate means for the cutting of undulatory gaps, the figures showing the parts respectively in elevation and in plan view.—Fig. 12 shows part of a comb obtained with the device according to Figs. 10 and 11.—In Fig. 13 another exemplification of means is shown for the cutting of undulatory tooth gaps.—Figs. 14, 15 and 16 are respectively sections through band-like cutting tools.—In Figs. 17 to 21 means are shown for the use of circular sawing or milling knives or blades as cutting instrumentalities and Fig. 22 shows a comb obtained for instance by the use of the means according to Figs. 17 to 21.—Fig. 23 is a section through a circular knife.—Fig. 24 is a modified form of construction of the device illustrated in Figs. 17 to 21, and Fig. 25 shows shaping means provided with stamping or punching knives.—Fig. 26 illustrates a combination of thick and thin circular blades mounted upon a common shaft.—Figs. 27 and 28 show a modification of cutting means respectively in elevation and in plan view.—Fig. 29 illustrates an individual lamellar guide.—Fig. 30 illustrates another exemplification of the invention diagrammatically and in side view and Fig. 31 is another embodiment of the cutting arrangement in elevation with parts in section, and Fig. 32 illustrates a substantially band-like knife.

In the exemplification embodied in Figs. 1 to 3 a shaft 68 is journaled in a supporting frame or base 67 and is shown provided with a crank arm 66 and crank pin 65 which by means of the link rod 64 and the pin 63 is adapted to vertically reciprocate the slide 10 which is guided along the pillars 20 and 21. Upon these pillars a plate 74 is secured which carries the frame 2 with the guiding lamellæ 3 for the knife 9. These guiding means serve also as support for the piece of work 18. Between the ends of the guiding leaves or lamellæ 3 (compare Fig. 3) elastic or preferably resilient spacers 4 are arranged as for instance resilient or spring acting disks, rubber plates or other elastic means. It appears from Fig. 3 that the lamellæ with the spacers 4 are firmly secured in position between stops 5 which are adjustable by means of screws 6 and 6a or similar means. It is possible by this arrangement to cause the distance between the first and the last guiding blade or lamella to exactly correspond to the distance between the first and the last teeth

or depressions or grooves provided in the piece of work.

In Figs. 5 and 5a some modifications of this kind of supporting frame and of the spring acting spacing means have been illustrated. In these figures showing the lamellæ on a greatly enlarged scale only 8 lamellæ are shown as an exemplification in order to save space, but it is obvious that a far greater number may be used, and the same applies to that part where five lamellæ for coarse teeth are shown, while the other lamellæ are intended for fine indentation. In these spaces between the lamellæ for fine indentation the knives guided therein have been omitted, while in the spaces for coarse indentation substantially conical blades are shown. The first five lamellæ 3 at the left-hand part of the drawing are straight and the intermediate spacers 4c are curved in such a manner that they will be held between the lamellæ 3 under a certain tension produced by the compressing screws 6a shown on the left hand end of the drawing. The sixth, seventh and eighth lamellæ 3c for fine indentation are curved at both ends in the direction of the interposed spacing means 4 which in this case may be straight and they are likewise tensionally engaged with each other. The lamella 3d shown somewhat in the middle of the drawing and constituting the first lamella for coarse indentation is stationarily secured in the frame 105 2', in order to prevent the transmission of the pressure of the thicker spacers 4c produced by the right-hand compression screws 6 onto the spacing means for the thinner teeth or lamellæ for fine indentation. Between the straight lamellæ for coarse indentation curved spacers are provided and kept under tension. In the spaces between the lamellæ for coarse indentation bevelled knives 9 for the production of bevelled tooth gaps are shown which are guided by the guiding lamellæ 3 for half of their width only. Whenever it is desired to guide the bevelled knives 9' for a larger portion of their width one may proceed by replacing one ordinary lamella by two lamellæ 3f of half the width of the ordinary lamellæ, these 120 lamellæ being so positioned as to adapt themselves to the conical parts of the knives 9' in such a manner that the ends of the lamellæ 3f may be curved with the insertion of curved or even straight spacing means. It is of course not necessary to employ all the different modifications illustrated in Fig. 5 on one and the same device it being, of course, preferable to employ one kind of operating means only.

It is evident that by the tightening or releasing of the pressure screws 6, 6a the spaces between the lamellæ or thin blades may be varied, so that the desired rate of indentation may be easily controlled which corresponds to the distance from the first to the last tooth of the comb. 135

In Fig. 5a the curved and tensionally disposed spacing means 4c are arranged symmetrically in the left side group with relation to the lamellæ 3 with the advantage that the lamellæ are more uniformly compressed thereby. To the right of 140 this group two spacers 4e are shown possessing two curvatures. In a similar manner the spacing means or the lamellæ may possess any other configuration adapted to admit an elastic deformation at the points of engagement under pressure 145 or they may consist of an elastic or resilient material, such as rubber for instance, and may then possess any desired shape.

In this connection it should be pointed out that elastic spacing means possess the important ad- 150

vantage that lamellæ and spacing means, as obtained by the rolling process, could heretofore hardly be manufactured with a greater accuracy than with slight variations of plus or minus ($\pm$) 5 0.01 millimeter and this fact would, in the event of using unelastic spacers produce a deviation of altogether $\pm$ 2 millimeters with for instance 100 lamellæ and 99 spacers, while on the contrary with the employment of elastic or resilient spacing means, disks or the like an absolutely accurate adjustment becomes possible.

In the exemplification of Fig. 1 the spaces between the lamellæ 3 serve for the guiding of the knives 9 which are secured at their lower ends to a support 11a and at their upper portions are fastened indirectly to the guide rods 69 which latter are connected to the sliding member 10. The securing of these knives 9 is preferably also effected between adjustable stops as appears from Fig. 20 7a and by the insertion of elastic spacing means between the several knives according to Fig. 3, so as to cause the distances between the cutting knives to conform exactly or approximately to the preliminary impressed grooves indicating 25 the teeth. Upon the lamellæ 3 which are disposed in the frame 2 the comb rests with its lower side. The comb is retained from above by lamellæ 3a which extend between the knives and are supported at the rear side of the machine in the following manner. Two double-armed levers 91 are fulcrumed on the shaft 92 by means of supports 98 (Figs. 1 and 2). The two levers 91 are connected to each other by a bar or the like 93 upon which a preferably somewhat resilient support 95 (Fig. 1) consisting for instance of soft copper, lead or of any suitable non-metallic substances such as for instance leather, is disposed as a carrier for the lamellæ 3a. These lamellæ 3a are also engaged by the shaft 92, so that as a result 40 of a pressure upon the levers 91 in the direction of the arrow (Fig. 1) the lamellæ are forced with their front ends against the comb 18 by the upward movement of the connecting bar 93, while the shaft 92 remains in its relatively fixed position, so as to arrest and retain the comb during the cutting operation. Between the lamellæ 3a and the shaft 92 elastic washers or insertion means may be arranged, as shown for instance in Fig. 31 of the drawing. Between the lamellæ 50 3a themselves similar kinds of elastic or resilient insertion pieces or spacers 4a may be disposed which are compressed by tensioning screws or the like 97 (Fig. 1) in cams or the like 96 on a shaft 94 and which may consist of rubber or the like, the action of the screws 97 upon the spacers 4a resulting in producing the proper adjustment to conform to the preliminary impression in the piece of work corresponding to the teeth of the combs under treatment.

60 Although by proceeding in this manner the lamellar guides 3 which serve as support for the comb 18 as well as the lamellæ 3a which serve for the depression of the comb are given their proper position for the correct guiding of the knives 9' during the cutting operation, still this arrangement is sometimes not sufficiently accurate to avoid objectionable deviations particularly in view of the forces generated during the cutting of the tooth gaps which are liable to cause irregularities. 65 In view thereof it will be advisable in certain cases of the treatment of blocks of working pieces with previously impressed teeth to employ the means hereinafter set forth, in order to insure the production of accurate gaps and teeth.

75 Such means are shown in Fig. 4 of the draw-

ings which is a sectional representation on the line V—W of Fig. 1 and on an enlarged scale from which the retaining of the comb 18 between the lamellæ 3 in the frame 2 and the lamellæ 3a in the depressing means can be seen. The lamellæ 3 and 3a are constructed or arranged in such a manner that they admit of lateral movement. This movement may for instance be readily provided for by effecting the mounting of the lamellæ by the use of spring acting spacing means in the manner hereinbefore described. This object may also be produced if the lamellæ are secured only at one of their ends and are free to yield or to spring actingly move sideways in view of their elasticity. According to another modification the lamellæ are not stationarily arranged but are only loosely secured, so that they may be laterally displaced for a certain limited distance. Other means may be used for this purpose or several of the means referred to may be used simultaneously with the result that the lamellæ are free to move laterally in the manner described, that is to say vertically with relation to their supporting plane. The lamellæ are also provided at their sides confronting the comb 18 with notches or recesses 98 (Fig. 4) which become engaged with the preliminarily impressed comb teeth and will become adjusted and conform to the configuration of these teeth, so that the said lamellæ 3 and 3a encompass and grip the preliminarily impressed teeth which become engaged with the recesses 98. Inasmuch as the knives 9 are guided below the comb between the lamellæ 3 and above the comb between the lamellæ 3a, the knives 9 are compelled to accurately cut the gaps between the previously pressed teeth or ribs. In the exemplification described the lamellæ 3a are freely adjustable in this manner independently of the employment of elastic spacers 4a as a result of the elastic nature of the lamellæ 115 themselves, inasmuch as they are secured at one side only. The same applies to the knives 9 which may also be secured at their ends by means of elastic spacing means. This arrangement however is not absolutely necessary with the embodiments of the invention as shown for instance in Figs. 1, 4 and 31, inasmuch as with these arrangements the knives in view of their great 120 length are sufficiently flexible and freely movable even without special spacing means, so as to adapt 125 themselves in the lateral direction to the position of the guiding lamellæ 3 and 3a.

In order to dispense with the, for instance horizontal relative movement of the pieces of work and of the band-knives with relation to each other in the cutting of the tooth gaps and by the use of symmetrically arranged knives, that is to say by using knives of the same width, the knives 9 are secured in position in such a manner that they extend in a direction forming an angle with their direction of movement, as shown for instance in Fig. 1 of the drawings. They cut out the tooth gaps by a kind of punching movement during their descent. At the point 9b the cutting edge is interrupted or terminated or the cross-section of the knives is reduced. This point 9b corresponds to the point where the cutting of the gap is to be terminated. As soon as this point 9b of the cutting tools has been moved sufficiently within the gap just produced the comb becomes disengaged or almost disengaged from the cutting edge, so that the comb is only loosely retained by the cutting means and may be readily detached therefrom after the raising of the depressing lamellæ 3a by means of the lever 91, 135 140 145 150

or it may be easily ejected from the cutting device by simple instrumentalities not shown.

Another exemplification embodying means of cutting the gaps in one operation without relative movement of the piece of work and of the band-knives in horizontal direction is illustrated in Figs. 6 and 7 of the drawings. In this modification knives 9" are shown, the cutting edge 22 of which extends in a direction different from that of the longitudinal axis of the knives. By this means the same result will obviously be produced which is obtained by the inclined positioning of the band-knives 9 with parallel edges in Fig. 1. The manner of operation is the same and the same parts as in the other figures are indicated by the numerals used in Figs. 6 and 7 of the drawings. If the upper knife edges 142 of the recessed part 9c in Fig. 7 of the drawings has been moved somewhat below the comb at the termination of the cutting action, the comb 18 becomes disengaged from the knives and may be released without being interfered with by the knives. As appears from Figs. 7 and 7a, the knives may be connected at their upper ends to the guide rods 69 and to the slide 10 by the parts 60, 61 and 62, and at their lower ends by the parts 11, 11a and 11b.

The form of construction of the knives 9" illustrated in Fig. 6 of the drawings is particularly adapted among other purposes for those kinds of applications of the invention in which it is desired to cut two combs in one operation with one cutting step of the device. For this purpose it would only be necessary for instance to make the knives 9" symmetrical as indicated by the dotted line 22a and to provide teeth at the cutting edge 22a likewise. By combining knives of this arrangement with suitable means corresponding to the other side of the device an additional piece of work 18a may be supported at the other side of the knives 9", so that upon the descent of the particular knife 9" in the direction of the arrows 50 two combs may be cut in one operation.

The modification of the knife shown in Fig. 6 possesses the additional advantage that it allows of the cutting of bevelled tooth gaps, that is to say of gaps in which the width of the gaps increases towards the ends of the teeth, this object being attained in a very simple manner by this modification. Figs. 6a to 6d illustrate the sectional shape of the knives 9" for bevelled tooth gaps in different horizontal sectional planes. As appears therefrom it will be sufficient to employ a band of steel the cross section of which corresponds somewhat to that shown in Fig. 6a, aside from the undercut formation of the edge. With knives 9" of this configuration bevelled tooth gaps may be obtained. The serrated cutting edge 22 of a bevelled knife of this kind will cut a bevelled gap without lateral teeth, because the thickest part of the cutting edge cuts first and thereafter the cutting edge and the cutting teeth and the cut gap are gradually becoming narrower, as the cutting operation proceeds. The same result may however also be produced with knives such as shown for instance in Fig. 1, but in that case the advantage could not be utilized of producing these knives from bevelled rolled steel bands, if lateral teeth are to be avoided. In that case the entire cutting portion of the band-knives may be bevelled by grinding in the upward direction. In the modification shown in Figs. 6, 6a etc. it is sufficient to cut away part of the material so as to

produce a bevelled cutting edge of gradually increasing thickness.

From an inspection of Fig. 6 another important improvement will appear. The teeth of the cutting edge which are intended to cut the last portion of the gap, for instance the teeth at the point indicated by the letter α in Figs. 1 and 6 may be rounded, for example of semi-circular shape. In view thereof the base of the tooth gap becomes semi-circularly shaped without it being necessary to round off all the other teeth of the cutting knives.

Instead of the arrangement of the upper frame 2a' for the upper guiding lamellæ illustrated in Fig. 7, it is of course also possible to employ lamellar guides 3a in the arrangement according to Fig. 1 with the advantage that the piece of work may be easily inserted and withdrawn and that it remains exposed and visible during the cutting operation.

It is of course advisable to provide coupling means of known construction for the purpose of interrupting the operation of the driving means of the machine after the termination of an operating stroke, that is to say, after the cutting of a comb. This interruption may for instance be effected in the lowest position of the knives immediately after the termination of the cutting operation; or the machine is arrested only after the knives have been returned to their highest initial position. It has already been mentioned heretofore that it is always preferable to have the knives substantially in their lowest position with a view of raising the depressing lamellæ and of ejecting the piece of work. It is also within the scope of the invention to provide suitable automatically acting ejectors for this purpose. If the operation of the machine is interrupted in the lowest position, it will of course also be necessary to arrest the machine after the following upward stroke, in order to be able to insert a fresh piece of work.

In the modified construction according to Fig. 9 the mounting of a plurality of guiding lamellæ 3 between curved side walls 7 has been shown in plan view. The curvature of these side walls corresponds to the shape of the arc which is formed by the feet of the teeth in many kinds of combs. The arc-shaped modification of the device according to Fig. 9 would for instance be of advantage for the cutting of combs such as has been illustrated for instance in Fig. 8 of the drawings. In an analogous manner the upper guiding lamellæ may also be secured in position, it being of importance in each case that the knives are secured between arc-shaped bounding pieces 60, 62 as shown in Fig. 7a by which means the important result is produced that with one set of knives of the same shape and size it is possible to cut teeth gaps without any additional auxiliary means the feet or starting points of which are arranged on an arcuate line. This curved arrangement may be adapted to the required conditions and may for instance be in the shape of a double arc. By the employment of cutting tools constructed in the manner of band-knives by means of which the gaps are cut out in a single stroke similar to the actuation of the needle-like instrumentalities for the formation of grooves it is possible to also manufacture undulatory tooth gaps. Two devices of this kind with the comb produced thereby are shown as an exemplification in Figs. 10 to 13. In this exemplification knives may be used with preference such as are shown for instance in Figs. 6 and 7 of the draw-

ings. With this kind of knife that part of the cutting edge 22 which extends at an angle to the vertical direction is curved, so as to present an undulatory line in the vertical projection. In this manner it is possible to produce wave-like or undulatory gaps 31, as shown in Fig. 12. As appears from Fig. 11 the guiding lamellæ 3 of the support for the piece of work under operation and also the lamellæ for the depression of the piece of work should be of undulatory shape to correspond to the wave-like formation of the gaps to be produced. In Fig. 11 only one knife 9'' and in Fig. 12 only three tooth gaps with the corresponding knives and guides have been illustrated with a view of simplifying the drawing, but it is obvious that this exemplification of the invention may likewise be provided with a sufficient number of knives to allow of all the gaps of the comb to be cut in one operation. The arrow 20 50 indicates the direction of movement of the knives 9''.

Fig. 13 shows another modification of the tool according to this invention in which the cutting edge 9a of the knives 9''' is parallel to the direction of the pull of the device, so that the comb 18 with the frame 2 and the lamellæ 3 must be displaced during the cutting operation in the direction of the arrow and at an angle to the cutting edge. In view of the fact that in this modification the cutting of the teeth is finished upon the descent of the knife the knife 9''' moves in the direction of the dot-and-dash arrow, the upper edge 17 of the knife moving in this manner with relation to comb 18. If the knife 9''' and the lamellæ 3 are undulatory similar to what is shown in Figs. 10 and 11, in order to cut undulatory gaps, the axes of the waves must be parallel to the dot-and-dash arrow direction of the relative movement of the knife edge 17 with relation to the comb 18. In the representation of the knife 9''' in this Figure 13 a shading is shown which is intended to indicate the direction of the waves. It should however be pointed out that the device according to Fig. 13 is also adapted to cut straight teeth with knives without undulatory parts, that is to say by means of straight or conical knives. In Fig. 13 the spacing blocks 4 are not used as rear supports for the knives as has been shown in Figs. 6 and 9, but rollers 140 are employed in the modification of Fig. 13. The kind of back support referred to is entirely dispensed with in the case of parallel knives as shown for instance in Figs. 1, 30 and 31. The depression unit is not shown in Fig. 13.

In each case it is of advantage and sometimes even necessary to undercut the cutting tools at the rear of the cutting edge. The knives according to Figs. 14 and 15 are provided with two cutting edges (in accordance with the exemplification of Fig. 1) in order to be able to use both edges or to use the second edge after the first one has been used up. Fig. 16 is a section through a band-knife with only one cutting edge 22. The undercut part is indicated at 172 in all of these figures. This arrangement accomplishes the known purpose of reducing the thickness of the cutting edge 22 directly to the rear of the edge and it produces the additional advantage that the knives will not rub with their entire surface upon the cut out teeth during the cutting operation, so that by this means undesired heating, packing and squeezing and other undesirable strains are avoided.

By the employment of circular knives, that is to say circular saws or milling knives as a cutting

tool for great masses of working pieces it is only possible to manufacture straight or bevelled gaps, the bevelled gaps being produced by a correspondingly bevelled configuration of the circular knives and by the arrangement of lateral teeth upon the circular knives. In this case it is evident that the guiding lamellæ 3 and 3a will not guide the bevelled circular saws upon the laterally indented part of the circular knives, but only at those places at which the lateral indentation ceases. The manufacture of undulatory tooth gaps cannot be effected by means of circular knives. In many cases however the employment of circular knives is of great advantage in view of the fact that they make it possible by their infinitely long cutting edge to cut the tooth gaps with shorter chips. This is a point of advantage in the cutting of tooth gaps in material that can only be cut with difficulty, but in many other cases also. Moreover this arrangement saves more space than in the case of band-shaped knives. The employment of a plurality of circular saws mounted on a common shaft for the cutting of the gaps of a comb simultaneously in one operation or for the purpose of cutting the gaps in groups has been suggested in the prior art but these suggestions fail to produce satisfactory results mainly on account of the fact that with the previous arrangements it was neglected to provide for the necessity of an exact guiding of each individual circular knife in accordance with this invention. The speed of rotation of the circular knives should be sufficiently low to avoid injurious heating of the circular knives and of the guiding lamellæ and of the comb itself.

In Figs. 17 to 24 a modified construction of the invention is shown in which a cutting tool operating on a plurality of working pieces and comprising a combination of circular knives is shown by way of illustration. Upon a base plate 115 supporting blocks 129 are arranged in which the shaft 101 of the circular knives is journaled and upon which the circular knives 100 with key and feather are disposed, as shown in Fig. 17. The circular saws or milling knives 100 are adjustably mounted in definite adjustable spaced relation to each other by means of compressible spacing disks or washers 103, for instance of rubber, and are secured in position by the hub 128 and the threaded ring 127. The outer edges of the circular saws 100 which are adapted for the cutting out of straight or of parallel tooth gaps project into the spaces between the lamellæ 3 and 3a which are arranged and constructed so as to serve as supports and as depressing means for the comb 18, and are guided in this manner. The guiding of the circular saws or milling knives in the previously determined cutting plane or approximately in this plane may be assisted by the use of additional guiding lamellæ 104 and 105, so that the circular saws are guided at three points of their periphery. With this kind of arrangement the spacers 103 may be entirely dispensed with, so that the circular saws 100 may be freely displaceable in the axial direction upon the shaft 101 and are only retained in their cutting plane by means of the lamellæ 3, 3a, 104 and 105. Obviously it is possible to use only one or more than two guiding devices instead of the two additional guiding devices 104 and 105 shown in the drawings. Thus, it has for instance been assumed in Fig. 18 that only one additional guiding device 104 is arranged diametrically with relation to the guiding lamellæ 3, 3a.

Upon the base plate 1 a frame 2x is displaceably

- disposed in which the guiding lamellæ 3 are arranged between which spacing means 4 are arranged which are preferably of resilient material such as for instance rubber washers, curved metal 5 disks or the like which are forced against each other by the screws 6, 6a (Fig. 18). Moreover a cover plate 124 is provided (Fig. 17). Upon the frame plate 2a* (Figs. 17 and 20) a shaft 92 is mounted by means of the supporting block 123. 10 This shaft carries two levers 91 which are connected to each other by a cross bar 93. Upon this cross bar 93 a support 95 is mounted which is preferably made of resilient yieldable material such as for instance leather upon which the 15 lamellæ 3a (Figs. 17 and 20) are adapted to rest. These lamellæ 3a are laterally retained by the screws 112 passing through the angle pieces 113 (Fig. 20) upon which a cross connection 114 with an intermediate layer or washer 94 is arranged. 20 Between the spacers 3a there are preferably arranged additional elastic spacers 4a of the same kind as the spacers 4 (Figs. 17, 19 and 20).

Between the lamellæ 3 and 3a in Fig. 17 the comb 18 to be cut is disposed which is retained in 25 position by the edges of the edgewise disposed lamellæ 3 and 3a and is secured against displacement by a rear support 125. The front edges of the lamellæ 3, 3a at the points engaging the comb and retaining it between them are provided with 30 oppositely directed projections 3g. A clamp 108 with screws 111 for the lamellæ 3a and a clamp 109 with screws 110 for the lamellæ 3 impart a certain position to the outer lamellæ in the vicinity of the circular saw for the purpose of guiding 35 the two outermost circular saws. For the same purpose the screws 126 are provided for the lamellæ 104 (Fig. 18) at the right-hand side of the circular saws. It is preferable to make the outer lamellæ correspondingly stiff and thick as shown 40 for instance in Fig. 18 with regard to the two terminal lamellæ 3i. This kind of reinforcement of the outer lamellæ is moreover advisable in connection with all the other exemplifications of the invention, that is to say for those exemplifications 45 also in which band-knives or punching or cutting dies are employed and generally speaking, wherever the guiding lamellæ are not secured in a frame and encompassing them on all sides. Thus, 50 the use of such reinforced terminal lamellæ would for instance be of advantage in the depressing means according to Fig. 1 or in accordance with the arrangement of Fig. 31 hereinafter referred to.

The forcing down of the upper lamellæ 3a in 55 Fig. 17 upon the comb 18 may for instance be effected by means of a tensional spring 120 (Figs. 17 and 20) which is suspended from the pin 121 and is secured in position by this pin and the pin 122 and the center line of which, as appears from 60 Fig. 17 in the operating position of the device herein shown, passes on the right side of the center of the axis of oscillation of the shaft 92 to the point 117. In this position the spring 120 will therefore have a tendency to force the lamellæ 65 3a downwards in the direction towards the lamellæ 3, so as to securely retain the comb 18 inserted between them. By swinging the lever 91 towards the left in Fig. 17 the center line of the tensional spring 120 is shifted towards the point 70 118 so that it will now be positioned to the left of the center of the shaft 92 so that the levers 91 will stop in this terminal position likewise as a result of the pull of this spring. In this terminal 75 position the lamellæ 3a are lifted off from the

comb 18, so that the indented comb may be withdrawn and a new comb inserted for treatment.

This automatic depressing or lowering means or equivalent depressing or retaining means for securing the depressing means upon the piece of work during the cutting operation is preferably employed wherever the comb is clamped between the lamellæ during the cutting operation.

The reciprocating movement of the comb support and of the depressing means with relation to the circular saws is for instance effected by means of a cam 116 acting upon the driving shaft 115 which is engaged with the frame plate 2a which latter plate is displaceable along the guides 130 on the base plate 1 (Fig. 20). Evidently however 90 it is also possible to use other guiding means employed in connection with machine tools which are adapted to produce for instance a slow advancing feed towards the circular saws and a rapid return. It is also possible to advance the 95 shaft 101 of the circular saws during the cutting operation of the teeth in the direction towards the piece of work 18 or to rock the shaft in this direction instead of moving the comb support and the depressing means. For this purpose the arrangement may for instance be such that the supporting means 129 may be displaceably or rockably mounted upon the base plate 1 and may be provided with a corresponding driving device. It is possible moreover to move both parts of the 105 device, that is to say the comb support as well as the circular saws with relation to each other during the cutting operation. In every case it is of importance that the circular saws 100 and the comb 18 should only be moved relatively to 110 each other to an extent which is determined by the depth of the gaps to be cut.

The circular saws may be of equal diameter, whenever the feet or starting points of the teeth are arranged in alignment with each other. The 115 diameters are of different length as shown in Fig. 18 when the feet or starting points of the teeth are arranged along an arc as also shown in Fig. 22. The circular knives are preferably laterally ground so as to be undercut as shown 120 for instance in Fig. 23 in two different modifications at 131 and 132.

The arrangement shown in Figs. 17 to 20 is particularly well adapted for the treatment of blocks with previously impressed teeth for combs 125 in such cases where the lamellæ 3 and 3a are provided with recessed parts 98 upon their narrow sides facing the comb 18, as shown for instance in the sectional view Y—X of Fig. 17 which is 130 illustrated on an enlarged scale in Fig. 21. The arrangement of elastic or resilient distance pieces 4, 4a between the lamellæ 3, 3a and the adjustable stops 5 and 112 for the lamellæ make it possible in the manner hereinbefore described to adjust the distance between the first and last guiding lamella before the beginning of the treatment 135 and so as to exactly correspond to the distance between the first and last tooth of the piece of raw material to be treated. The same applies however for the cutting knives also, whenever 140 required. Still, in this form of construction as well as in the forms of construction according to Figs. 1 to 3 already referred to the final degree of accuracy may be accomplished by causing the recessed parts 98 of the lamellæ to grip 145 or grasp and encompass the previously impressed teeth, so as to compel the lamellæ to become laterally adjusted in such a manner that each lamella is centered so as to exactly correspond to the center of the particular tooth. There is 150

this possibility of accurate adjustment for the lamellæ 3 and 3a in view of the insertion of the elastic intermediate and spacing pieces 4 and 4a. In the form of construction herein shown the 5 lamellæ 3 and 3a possess a laterally spring acting resiliency even without such elastic inserting pieces in view of the fact that the lamellæ are secured at one side only and possess a sufficiently high degree of elasticity of their own in order to 10 allow them to oscillate laterally. Inasmuch as the circular saws are guided between the lamellæ 3 and 3a and in the immediate vicinity of the cutting point they are forced to exactly cut out the gaps between the previously impressed teeth 15 of the comb.

In Fig. 24 an instrumentality is shown in which the comb retaining means are swingingly or colapsibly arranged for the purpose of facilitating the insertion and removal of the pieces of work. 20 For this purpose the frame plate 2a', instead of being displaceable upon the base plate 1, is rockably mounted in eyes 134 of an intermediate plate 2b by means of studs or bolts 133, this intermediate plate being displaceably mounted on the 25 base plate 1. In this arrangement it is also possible to connect the plate 2a' to the base plate 1 in such a manner as to be directly rockable thereupon, in which case the shaft 101 of the circular saws of the supports 129 thereof may be displace- 30 ably or rockably mounted.

In the disengaging movement of the depressing and retaining lamellæ 3a from the comb 18 in Fig. 17 the lamellæ 3a in the event of a correspondingly large elevating movement may be 35 moved out of engagement with the circular saws. If the comb support in the upward rocking movement illustrated in Fig. 24 is moved sufficiently, the lamellæ 3a alone or 3 and 3a will become 40 disengaged from the circular saws guided thereby. During this disengaging position there is a 45 liability of slight relative displacements of the saws 100 taking place with relation to the guiding lamellæ particularly in case elastic insertion pieces 103 have not been placed between the circular saws. In such cases there would be the 50 danger that, when the lamellæ 3 and 3a are moved back, the edges of the lamellæ would become engaged with the cutting edges of the circular saws 100. In order to avoid this difficulty 55 it is of importance to chamfer off the lower front edges of the lamellæ 3 and 3a in the manner shown for instance at 3h in Fig. 17 of the drawings. Another possibility of overcoming this difficulty is shown in Fig. 24, where the supporting 60 lamellæ 3 at their front edges are provided with downwardly directed curved projections 141 which are constantly retained in engagement with the circular saws.

It is of course advisable to arrest the circular 65 saws during the exchanging of the comb.

It should be pointed out that, particularly in the case of cutting combs with impressed ribs indicating the teeth, the guiding of the circular saws is mainly effected by the guiding lamellæ 3 and 3a. The function of the additional guiding means 104 and 105 is therefore mainly confined to the prevention of an appreciable edging or tilting of the circular saw blades, inasmuch as the depth of the hub of these circular saw 70 blades will ordinarily not exceed the thickness of the saw disks for reasons of lack of space and on account of other manufacturing purposes. It results therefrom that under ordinary conditions the guides 104 and 105 will be so adjusted that the individual saw blades are guided between them

somewhat more freely so as to allow them to conform without difficulty to the delicate adjustment by means of the lamellæ 3 and 3a.

It may also be pointed out in this connection that the guiding devices 104 and 105 are not absolutely necessary and that they may be dispensed with wherever the device is arranged in such a manner that a set of circular saws is centrally disposed between two or more comb retaining means. In this case the circular saw blades would be satisfactorily guided by the guiding lamellæ 3 and 3a of the existing comb supports at several points of their periphery. An arrangement of this kind may for instance comprise a set of circular saws and two comb supporting means arranged 80 in horizontal alignment with relation to each other.

Another modified construction of the means for effecting the simultaneous cutting of a great number of gaps and substantially operating in a manner similar to dies and punching tools is shown in Fig. 25 of the drawings. The knives 19 which operate somewhat like cutting dies are provided with shouldered projections 19' by means of which they are continuously guided, 100 particularly from the beginning of the cutting operation in the gaps between the supporting lamellæ 3. The guiding lamellæ above the comb in this modification, instead of serving as depressing means for the comb are only intended 105 to serve as knife guiding means and as a strike-off for the comb 18, but it is obvious, of course, that the guiding lamellæ 3a above the comb 18 may also be constructed to serve as depressing means.

The shoulder-like projecting parts 10 required to be guided between the supporting lamellæ 3 only during the cutting operation itself, but it is of course admissible and may sometimes even be of advantage to allow them to remain in permanent engagement with the supporting lamellæ. In this manner the principle of this invention is realized by means of the cooperation of the guiding shoulders 10 with the lamellæ 3, so that the cutting tool is accurately guided during its 115 operation. It is obvious that all the other forms of construction and modifications described may also be used with the employment of dies or punching tools, particularly the independent adjustability of the supporting and depressing 120 lamellæ after the preliminary impression in the case of using the crude block with previously impressed indications for the teeth.

In Fig. 26 and in accordance with the arrangement of the stationary lamella 3d in Fig. 5 there is illustrated an arrangement of groups of comparatively thick circular saws 100a and of thick spacing disks 103a intermediate these saws and of another group of thin circular saws with thin spacing disks 103. The shaft 101 is provided with 130 a shoulder 101a against which the last thick circular saw 100a is adapted to rest, so that the pressure produced by the tensioning nuts 127 is prevented from being transmitted from the thick spacing disks 103a to the thin spacing disks 103, 135 which is of advantage in the case of elastic spacing disks. In this case likewise only a small number of circular saws has been shown as compared with what is ordinarily used in practical operation.

In Fig. 27 I have shown in elevation and in Fig. 28 in plan view and in horizontal section through the knives 9x a modified construction in which instead of using a plurality of knife guiding means comprising a series of lamellæ arr-

ranged side by side of each other a guiding device is employed situated below and above comb 18 and comprising steel plates 144 and 145 in which there are slotted guides for the guiding of the knives, 5 as shown for instance by the guide slots 8 in Fig. 28. This form of construction is particularly adapted for cutting combs without previously impressed tooth gaps. In accordance with Fig. 28 the knife guides 144 and 145 need not necessarily 10 serve as support for the comb 18. In this modification the comb at its rear part is clamped in a known manner and similar to the action of a pair of tongs between the members 148 and 149. Member 148 is fixed on the plate 147 and the 15 member 149 is rotatably mounted on the member 148 by means of the pivot 146.

In Fig. 29 a shape of lamellæ is shown in edge-wise view which does not require any special spacing members inasmuch as this lamella is integral with the spacing member. 20

In Fig. 30 the same reference numerals indicate parts equivalent to those described. The support for the knives 9^x is indicated at 41. In this modification the knives are similar to those described with reference to Fig. 1, possessing longitudinal edges which are likewise inclined with relation to their direction of movement indicated by the arrow 50. There is that difference however over Fig. 1 that the knife support 41 25 is not guided exactly in the vertical direction, but at an angle with relation to the vertical direction, this result being accomplished by the engagement of pivots 42 of the support 41 with inclined guide slots 44 of the frame or support 43.

30 The knives shown in Figures 30, 6, 7, 13, 31 and 32 are provided at their upper end with a recess 9c which is of such a size with relation to the depth of the tooth gap produced that the knives 9^x after the termination of the cutting procedure 35 will become completely disengaged from the cut comb, so that the comb may be easily removed or may be withdrawn by being blown off by compressed air. The same recess 9c may also be used without difficulty in connection with knives intended for the machine according to Fig. 1. A 40 somewhat similar form of knife is also shown in the exemplification of Figs. 31 and 32.

The form of construction corresponding to Fig. 31 is similar to the exemplification of the machine according to Fig. 1 the differences residing 45 mainly in the shape of the knife, inasmuch as the recess 9c for one of the cutting edges is provided at the other end of the knife and on the other side of the knife opposite the cutting edge carrying the recess 9c. With this arrangement 50 it is necessary to interchange the upper and lower ends of the knives, whenever it is desired to use the knives with the second cutting edge. The recessed portions 9c may also be provided at the 55 same end of the knife as appears for instance from Fig. 32, but the modification according to Fig. 1 admits of manufacturing knives from a somewhat narrower steel band. The cutting edges of the knife are serrated. The two thin 60 lines in Fig. 32 which extend at the distance *a* from each other indicate the width of the undercut part of the knife.

In Fig. 31 there is shown the combination with 65 means to advise the operator of the termination of the cutting procedure and to cause him to raise the depressing means, in order to withdraw or to eject the comb, before the band knives 9^y return to their initial position. This object is 70 accomplished by providing the guide rods 69 or one of them by means of a bracket 160 with an

adjustable arresting stud 161 which at the end of the working stroke strikes against a corresponding stopping surface 162 of a lever 91 and thereby starts the upward movement of the depressing lamellæ 3a and which may be so arranged as to positively move these lamellæ for a sufficient amount to allow of the finished comb being removed or ejected. The modification of Fig. 31 shows moreover the additional feature that in the depressing means according to Fig. 1 80 the outer portions of the lamellæ 3a directly before the knives may be connected to each other by a bolt or stud 163. In this construction spacers 4a may also be arranged between the lamellæ 3a, these spacers being either elastic or being somewhat narrower than the proper distance of the lamellæ from each other which corresponds to the width of the gaps. In this case the lamellæ are also free to become adjusted in conformity with the previously impressed teeth, but the 85 spacers or distance pieces will reliably obviate the occurrence of appreciable errors in the position of the front ends of the depressing lamellæ. 90

It has already been pointed out that an automatic arrangement may be provided for the ejection 100 of the comb after the termination of the cutting procedure. The ejection of the comb may for instance be effected by means of compressed air. The operation of the cock of a compressed-air conduit may for instance be effected at about 105 the deepest position of the knives by stops in a similar manner as has been indicated in Fig. 31 for the raising of the depressing means, that is to say, by means of a stopping screw or the like 110 110 and stop 162.

As shown in Fig. 31, lever arm 91 opposite the stop 162 can be connected by means of a rod 263 with a valve 264 provided in the inlet-pipe 265 for the compressed air. Pipe 265 terminates in a nozzle 266 underneath the comb. As soon as the 115 adjustable stop 161 hits against stop 162 after the completion of the cutting operation, lever arm 91 is shifted and the depressing means is raised resulting in the opening of valve 264. The comb is now ejected by the compressed air. 120

The use of compressed air, aside from its use for the ejection of the comb is also of advantage for the purpose of removing the chips produced in the cutting of the tooth gaps, because it is undesirable to have the chips remain within the 125 frequently very small interstices between the several knives and lamellæ, which would cause sticking, clamping and other inconveniences.

With a view of showing the great adaptability of this invention the same has been shown and described herein in various embodiments of its principles, but it should be understood that the invention admits of further modifications and changes, in accordance with the demands of the trade and working conditions, without any departure from the principles of the invention. 130

I claim:—

1. A comb making device comprising in combination, sets of lower substantially blade shaped spacedly disposed guiding means arranged on edge and sets of upper spacedly disposed and substantially blade shaped guiding means arranged on edge, means adapted to move the upper and lower guiding means with relation to and from each other, so as to retain the piece of work therebetween, a plurality of parallel spacedly disposed cutting means alternating with and movable between said guiding means, and in engagement therewith and moving means for the cutting means. 140 145 150

2. A comb making device comprising a plurality of parallel, spacedly disposed guiding means and a plurality of parallel, spacedly disposed, guiding means above the other guiding means and movable toward and away from the former means, parallel spacedly disposed cutting members simultaneously movable between said guiding means and engageable therewith, and means to adjust and fix the distance between the individual guiding means and between said cutting members, and moving means for said cutting members. 50
3. A comb making device comprising in combination, a lamellar, substantially grate-shaped supporting unit for a piece of work and a lamellar, substantially grate-shaped depressing unit above the supporting unit and movable with relation thereto and adapted to grip a piece of work between the units, distance-adjusting and fixing means for each of said units and substantially lamellar grate-shaped cutting units entering between the other units and guided thereby, and moving means for certain of said units. 100
4. A comb making device comprising in combination, a plurality of substantially grate-shaped, resilient supporting units and a plurality of substantially grate-shaped resilient lamellar depressing units, means to move said supporting units and said depressing units into clamping relation with each other so as to retain pieces of work between them, distance-controlling and fixing means upon and between the parts of said units, cutting means guided between the parts of said units and into engagement with the work, and moving means for said cutting means. 150
5. A comb making device comprising in combination a plurality of parallel, spacedly disposed, substantially blade-shaped and supporting means for the work and constituting a supporting unit, a plurality of another series of spacedly disposed substantially blade-shaped and supporting means for the work and constituting a depressing unit and in alignment with the other unit, working material between the units and engageable therewith, securing means for each of said units at the ends thereof opposite the engaging units, cutting means movable between the blade-shaped parts of said units and guided thereby, distance-controlling and fixing means between and sideways of the blade-shaped parts of the units, and moving means for said cutting means. 200
6. A comb making device comprising in combination, a plurality of parallel, spacedly disposed resilient, substantially blade-shaped guiding means constituting a work-supporting unit, a plurality of another series of parallel, spacedly disposed resilient, substantially blade-shaped guiding means, constituting a depressing unit and above the supporting unit and in alignment therewith to clamp working material between the supporting unit and said depressing unit, moving means operatively engaging certain of said units and causing them to engage the working material at one of their ends, clamping means at the ends of one or both of said units opposite the material-engaging ends, elastic, indented gripping members at the opposite, material-engaging ends of the units, and cutting means movably guided between the parts of said units. 250
7. A comb making device comprising in combination, two digitated, spacedly recessed work-supporting units, resilient confronting aligning and indented work-gripping terminal portions on said units to receive a substantially parallelly fluted piece of work between said units and en-
- gagable with the indented portions thereof, and cutting means movable within the recessed parts of said units. 300
8. A comb making device comprising in combination, two substantially grate-shaped work-engaging units, movable with relation to each other to clamp a piece of work adapted to be engaged by and between said units and elastic compressible spacers in the recessed parts of said units, compression-controlling and fixing means on said units, and cutting means guided in the recessed parts of said units. 350
9. A comb making device comprising in combination, substantially grate-shaped work-engaging units, substantially endwise movable into work-gripping engagement, substantially grate-shaped cutting means, guided within the recessed parts of said work-engaging units, moving means for the cutting means, elastic compressible spacers in the recessed parts of the cutting means, and compression-controlling and fixing means on said cutting means. 400
10. A comb making device comprising in combination, substantially grate-shaped guiding units, terminal work-engaging means disposed on said units, band-like cutting means guided in said units and means on said cutting means imparting a movement to said cutting means in a direction forming an angle with the cutting edges of said cutting means. 450
11. A comb making device comprising in combination, substantially grate-shaped, endwise work-gripping and aligning guiding units, and edgewise longitudinally fluted band-like cutting means guided in said units. 500
12. A comb making device comprising in combination, substantially grate-shaped, endwise work-gripping and aligning guiding units, upwardly reciprocable band-like cutting means guided in said units, and moving means for imparting to said cutting means a movement in a direction forming an angle with the cutting edges of said cutting means, to permit cutting of the teeth of the comb with one stroke. 550
13. A comb making device comprising in combination, substantially grate-shaped work-gripping and aligning guiding units, a substantially curve-shaped cutting unit its curve corresponding to the shape of the arc formed at the base of the teeth of the comb, said unit comprising a plurality of parallel and spacedly disposed cutting blades, and means to move said blades between the recessed parts of the guiding units. 600
14. A comb making device comprising in combination, substantially grate-shaped, curve-forming and aligningly disposed work-gripping guiding units, their curve corresponding to the arc formed at the base of the teeth of the comb, said units comprising a plurality of parallel spacedly and edgewise disposed guiding lamellæ, and a plurality of parallel, spacedly disposed inter-connected cutting blades corresponding to the arrangement of the guiding lamellæ and guided in the interstices thereof. 650
15. A comb making device comprising in combination, grate-shaped guiding units, movable into work-engaging contact with each other and comprising sets of differently spaced guiding grates and substantially unyielding, separating and confining means between said sets and resilient spacing means in the recesses of said guiding grates and cutting means movably guided in the recessed portions of said guiding units. 700
16. A comb making device comprising a plurality of substantially elastic parallel, spacedly

- disposed guiding means, retaining means for said guiding means, elastic compressible spacing means inserted between said guiding means, cutting means movably guided between said guiding means and intermediate said spacing means, work-retaining means cooperating with said guiding means, and compression-controlling means cooperating with said guiding means.
17. A comb making device comprising in combination, substantially grate-shaped and aligning guiding means, a base on which said guiding means are rockingly disposed, cutting means guided within said guiding means, and elastic compressible spacing means in the recessed portions of said guiding means and intermediate said cutting means.
18. A comb making device comprising in combination, a plurality of inter-connected, parallelly spaced edgewise disposed substantially resilient blade-like members constituting a work-supporting unit and a plurality of inter-connected, parallelly spaced and edgewise disposed blade-like members constituting a work-depressing unit above said supporting unit, a rocking lever carrying said depressing unit, and cutting means projectingly guided in the recessed portions of said work-supporting and work-depressing units.
19. A comb making device comprising in combination, a substantially grate-shaped work-supporting unit and a substantially grate-shaped work-depressing unit aligningly engageable therewith, cutting means guided in the recessed portions of said units, and automatically operated means for removing the piece of work at the end of the cutting operation.
20. A comb making device comprising in combination, a substantially grate-shaped work-supporting unit and a substantially grate-shaped work-depressing unit aligningly engageable therewith, cutting means guided in the recessed portions of said units, and compressed-fluid admitting and discharging means adapted to be operated substantially at the end of the stroke of said cutting means to remove the piece of work by a current of compressed fluid.
21. A comb making device comprising in combination, a substantially grate-shaped work-sup-
- porting unit and substantially grate-shaped work-depressing unit aligningly engageable therewith, upwardly reciprocable cutting means guided in the recessed portions of said units, moving means for at least one of said units, moving means for the cutting means, and compressed-fluid operated removing means associated with said guiding units and adapted to remove the cutting chips from between the gaps of the piece of work.
22. A comb making device, comprising a substantially grate-shaped work-supporting unit and a substantially grate-shaped work-depressing unit aligningly engageable therewith, upwardly reciprocable cutting means guided in the recessed portions of said units and reduced beyond its cutting edge so as to release, and permit the removal of, the work, the cutting of which is performed within one stroke.
23. A comb making device, comprising a substantially grate-shaped work-supporting unit and a substantially grate-shaped work-depressing unit aligningly engageable therewith, upwardly reciprocable cutting means guided in the recessed portions of said units and shouldered beyond its cutting edge so as to release, and permit the removal of, the work, the cutting of which is performed within one stroke.
24. A comb making device, comprising substantially grate-shaped work-gripping and aligning guiding units, upwardly reciprocable band-like cutting means guided in the recessed portions of said units, the thickness of the cutting edge gradually decreasing in order to cut convergent tooth gaps, and moving means for said cutting means.
25. A comb making device, comprising a plurality of parallel, spacedly disposed, substantially blade-shaped guiding means constituting a work-supporting unit, a plurality of another series of parallel, spacedly disposed, substantially blade-shaped guiding means, constituting a depressing unit disposed above said supporting unit and in alignment therewith, to clamp the teeth of the working material between said supporting unit and said depressing unit, and cutting means movably guided between the parts of said units.
